Francis Blake

UNITED STATES PATENT OFFICE.

FRANCIS BLAKE, OF WESTON, MASSACHUSETTS.

TELEPHONE.

SPECIFICATION forming part of Letters Patent No. 314,312, dated March 24, 1885.

Application filed February 9, 1883. (No model.)

To all whom it may concern:

Be it known that I, FRANCIS BLAKE, of Weston, Massachusetts, have invented a new and useful Improvement in Speaking-Telephones, of which the following is a specification.

The invention relates to that class of telephone-transmitters in which a powdered or granulated conducting material forms that portion of the telephone-circuit the resistance of which is varied under the action of sound-waves. I employ a horizontal diaphragm which receives the sound-waves upon its under surface, and has a mass of powdered or granulated conducting material lying loosely upon its upper surface and forming the variable-resistance portion of the circuit. A mass of such material in a loose condition has a very high resistance as compared with the same mass in a solid or compact form, and the vibrations of the diaphragm under the action of sound-waves tend constantly to throw the loose conducting material upward and prevent it from becoming so compacted or compressed as to change the specific resistance of the mass.

One part of the invention relates to the construction of an electrode which is buried in the granulated material and admits such free movement thereof, and at the same time gives a large cross-section, and consequently a comparatively low resistance, to that part of the circuit. I am thus enabled to accomplish results with a single cell of battery which might otherwise require a larger number of cells.

Another part of my invention relates to a method of connecting the diaphragm with the electrode which is buried in the loose material, so that the diaphragm is strained, and so that the vibrations of the diaphragm shall affect the loose material more uniformly, and shall be communicated directly to said buried electrode. An unstrained diaphragm, by reason, probably, of differences of tension between different portions, is liable to vibrate differently under the action of sound-waves at different points equally distant from the center, and thus may fail to cause changes in the resistance of the loose material corresponding faithfully to the form of the sound-waves. The vibrations of the electrode due to its mechanical connection with the diaphragm assist in

maintaining the loose condition of the granulated material.

In the drawings, Figure 1 is a sectional elevation of my new transmitter embodying the above-mentioned improvements. Fig. 2 is a plan of the same with the clamping-plate and the granulated conductor omitted. Fig. 3 is a plan of the diaphragm. Fig. 4 is a plan of the sieve electrode. Fig. 5 is a plan of a non-conducting washer used to separate the diaphragm from the sieve electrode. Fig. 6 is a plan of a non-conducting post or block inserted between the diaphragm and the sieve electrode. Fig. 7 is a partial sectional elevation showing a modification.

All the parts are shown of full size, and I may add that after much experimenting I have found that the size and proportions shown are those best adapted for the use of the instrument with ordinary receivers.

A is the bed or support for the telephone, and contains the aperture through which speech is uttered.

B is a ring of non-conducting material resting on the bed A, and b is a metallic ring resting on the bed A within the ring B, and forming the seat of the diaphragm. In one form of construction the rings B and b are both of non-conducting material and are formed in one piece, the bed A in such case being omitted.

D is a metallic diaphragm, resting at its edges upon the ring or seat b. The diaphragm, as above stated, is one of the electrodes, and in practice it is connected with one of the circuit-wires through the seat b when that seat is metallic, or directly with such wire when the seat b is integral with the ring B and is of non-conducting material.

S is a wire sieve electrically separated from the diaphragm by a washer, w, of non-conducting material.

P is a metallic clamping plate having a boss or ring projection, p, that rests upon the sieve at the edges of the latter.

The plate P and the ring B have the same diameter, and so likewise the boss of the plate P, the sieve S, the washer w, the diaphragm D, and the seat b are equal in diameter; and accordingly the different parts of the instrument are held together by screws (I use but four) passing through the plate P and ring B,

and into the bed A when a bed is employed. Electrical connection is made between the sieve electrode S and its circuit-wire through the metallic clamping-plate P.

5 C is a finely divided or granulated conducting material (I use powdered carbon) filling the instrument above the diaphragm to within a short distance of the plate P. The grains are of a size that permits them to pass freely 10 through the sieve, which is buried in their mass. The plate P has a hole through which the granulated conductor is poured. This hole is closed by a screw-plug, E.

L is a post or block of non-conducting material inserted between the diaphragm and the sieve, thereby straining the diaphragm. It also gives to both the diaphragm and the sieve a conical form, and, being firmly clasped 20 between the diaphragm and the sieve, as between two springs, causes the latter mechanically to partake of the vibrations of the former.

When the instrument is connected up for use, as before stated, one wire leads to the diaphragm and the other to the sieve. The 25 diaphragm and the sieve thus become electrodes, the granulated conductor making the electrical connection between them.

Further description of the mode of operation of the instrument as a whole is unnecessary.

The instrument thus constructed will remain in adjustment, no matter what may be the character of the sounds falling upon the diaphragm. Vocal sounds transmitted by it are 35 remarkably faithful copies of the original, and, above all, the instrument is superior to all other telephones with which I am acquainted in preserving the loudness of the sounds transmitted. I will add, however, that while the 40 form of construction described and shown gives the best results as a whole I have found that some of the details of construction are advantageous to a greater or less extent independent of other details.

45 Thus the advantage derived from the action of a strained diaphragm acting upon loose material forming the variable-resistance portion of the circuit is not dependent upon the use of the diaphragm as one electrode, nor upon 50 the use of the sieve as the other electrode, but will be secured when either the diaphragm or the sieve is used for one electrode, and a ring at the outer edge of the loose material is employed as the other electrode—that is, in the instrument shown one of the circuit-wires may be 55 made to connect either with the diaphragm D or the sieve S, and the other with the boss p of the clamping-plate P; but when the sieve and the ring are made to serve as the electrodes of 60 the instrument represented in the drawings, they must be separated electrically by a washer. (For this construction see Fig. 7, where

the additional washer is marked w'.) Neither is the advantage which is due to the mechanical connection between the sieve and the diaphragm wholly dependent either upon the use of the diaphragm as an electrode or upon the use of the diaphragm in a horizontal position. There is great advantage gained as to loudness, even when the diaphragm is out of the 70 circuit, by rigidly connecting the center of the diaphragm with the sieve buried in the loose conducting material, so that the sieve will partake of the vibrations of the diaphragm, and this even if the instrument is turned up so as 75 to be used substantially at a right angle to the position shown. The present instrument may be so used by making the sieve serve as one electrode and the boss of the ring P as the other, inserting a non-conducting washer between them, and causing the sieve to partake 80 of the vibrations of the diaphragm in the manner now shown.

I claim—

1. In a telephone employing a granulated 85 conducting material as the variable-resistance portion of the circuit, two horizontal electrodes, one serving as the transmitting-diaphragm and carrying such material loosely upon its upper surface, and the other being a 90 sieve buried in such material and allowing such material to pass freely through it, substantially as described.

2. In a telephone employing a granulated 95 conducting material as the variable-resistance portion of the circuit, two horizontal electrodes mechanically connected to vibrate together, one serving as the transmitting-diaphragm and carrying such material loosely upon its upper surface, and the other being a 100 sieve buried in such material and allowing such material to pass freely through it, substantially as described.

3. In a contact-telephone employing granulated 105 conducting material as the variable-resistance portion of the circuit, a transmitting-diaphragm in mechanical contact with said granulated material, and an electrode buried in said granulated material and allowing said material to pass freely through it, the said 110 electrode being mechanically connected to the said diaphragm at the center of the latter to partake of its vibrations, substantially as described.

4. In a telephone employing a granulated 115 conducting material as the variable-resistance portion of the circuit, a transmitting-diaphragm carrying such material loosely upon its upper surface and strained to a conical form, substantially as described.

FRANCIS BLAKE.
